UNITED STATES PATENT OFFICE.

FLOYD J. BEERS, OF CHEMUNG, NEW YORK.

BOTTLED-BEVERAGE COOLER.

Application filed May 27, 1926. Serial No. 112,111.

This invention relates to certain new and useful improvements in bottled beverage coolers and has for its primary object to provide a receptacle or container for bottles 5 with the bottles supported in an upright position within the cooler and having their necks alone protruding above the cooler with flexible means carried by the cooler and engaging the neck of the bottle to hold the 10 same in an upright position and to prevent the entrance of air to the interior of the cooler.

A further object of the invention is to provide a bottled beverage cooler of the type 15 above set forth wherein the wall of the cooler is of double walled insulated formation with a central opening in the upper wall of the cooler for the reception of a block of ice and with a cover wall for the opening, 20 there being an overflow drain pipe to regulate the quantity of chilled water remaining in the cooler.

With the above and other objects in view that will become apparent as the nature of 25 the invention is better understood, the same consists of the novel form, combination and arrangement of parts hereinafter more fully described, shown in the accompanying drawing and claimed.

30 In the accompanying drawing, wherein like reference characters designate corresponding parts throughout the several views,

Fig. 1 is a top plan view of a bottled beverage cooler constructed in accordance with 35 the present invention,

Fig. 2 is a vertical cross sectional view taken on line 2-2 of Fig. 1 showing the insulated double wall construction of the cooler, the overflow water pipe and the removable cover for the ice receiving opening 40 in the upper wall of the cooler,

Fig. 3 is a detail sectional view on an enlarged scale, and

Fig. 4 is a fragmentary top plan view 45 showing the flexible bottle neck gripping member.

Referring more in detail to the accompanying drawing, there is illustrated a bottled beverage cooler comprising a container 50 that may be of any configuration desired, the same being herein illustrated as circular in top plan and embodying a lower body portion and a cover wall. The body portion is of double walled formation embodying an outer wall 1 and an inner wall 2 spaced therefrom to provide an area for insulating

material 3 such as cork or the like, the walls being spaced from each other as clearly shown in Figs. 2 and 3.

The cover for the container comprises a 60 flat wall 4 resting at its peripheral edges upon the upper edges of the inner and outer side walls 1 and 2 of the body portion, the cover wall section 4 having a central opening 5 surrounded by an upstanding flange or 65 neck 6. The cover also includes an upper wall 7 having a central opening to be received on the neck 6 and an annular depending flange 8 inclosing the outer side of the outer wall 1. A removable cover or lid 9 70 provided with a handle 10 is received on the upper end of the neck 6 and includes a depending side flange 11 inclosing the neck as clearly shown in Figs. 2 and 3.

The cover wall sections 4 and 7 are provided with registering openings 12 of a diameter to permit free passage of the bottle B therethrough as shown in Figs. 2 and 3 with the bottle supported at its lower end upon the bottom side of the inner wall 2 of 80 the container. To prevent ingress of air to the interior of the container through the openings 12, a flexible plate 13 of rubber, leather or the like is positioned between the cover wall sections 4 and 7 and said flexible 85 plates over the portions thereof spanning the openings 12 are radially slitted as at 14 to the central opening 15 to form flexible bottle neck engaging tabs 16 shown in detail in Fig. 4. The inner ends of the tabs 16 intimately engage the neck N of the bottle B and effectively seal the openings 12 against the passage of air into the container.

In the use of the cooler, the lid 9 is removed and a block of ice placed in the cooler through the central opening 5. By the provision of the upstanding neck 6 it is possible to place a larger block of ice in the relatively shallow cooler and the chilled water in the cooler will rise to the upper end of the overflow pipe 17 and flow outwardly of the cooler to prevent the water level rising to the bottle openings 12. Also, by the provision of the flexible tabs 16 engaging the necks N of the bottles, splashing of water through the openings 12 is prevented. The device is extremely attractive in appearance, and practically the entire bottle being housed within the cooler will insure a thorough chilling of the contents of the bottles while the character of the beverage will be displayed upon the bottle cap.

From the above detailed description of the device, it is believed that the construction and operation thereof will at once be apparent, and while there is herein shown and described the preferred embodiment of the present invention, it is, nevertheless to be understood that minor changes may be made therein without departing from the spirit and scope of the invention as claimed.

10 What is claimed is:—

In a bottled beverage cooler, a container comprising side, cover and bottom walls, the

said cover wall having a central opening and a removable lid, and having a plurality of openings for the insertion retention and removal of the bottles, to which are fitted radially slotted flexible rings, adapted to allow of the insertion and removal of bottles, and to embrace the necks of the bottles, when the latter are in position, and seal the openings against the admission of air to the container.
